UNITED STATES PATENT OFFICE.

AUGUST SEILER, OF NEW YORK, N. Y.

DESIGN FOR A TOP.

SPECIFICATION forming part of Design No: 31,017, dated June 13, 1899.

Application filed May 16, 1899. Serial No. 717,100. Term of patent 14 years.

To all whom it may concern:

- Be it known that I, AUGUST SEILER, a citizen of the United States, residing at New York, in the county of New York and State of New York, have invented and produced a new and original Design for Tops, of which the following is a specification, reference being had to the accompanying drawings, forming part thereof, in which—
- 10 Figure 1 is a plan view showing my newly-designed top in an upright position; Fig. 2, a central vertical section thereof, and Fig. 3 a side view showing a top in its normal position.
  - 15 As shown in the drawings, my newly-designed top comprises a body portion *a*, which is conical in form, the apex thereof being flat, as shown at *b*, and the bottom being also flat, as shown at *c*, and parallel with the top. The
  - 20 body portion is also provided centrally of the bottom with a projecting pin *d*, the end of

which is pointed, as shown at *e*; and centrally of the top portion thereof with a handle *f*.

The conical part of the body portion *a* is provided with a plurality of facets *g*, six of which are employed, and these facets are each provided with dots or characters *h*, ranging from one to six in number.

Having fully described my invention, I claim as new and desire to secure by Letters Patent—

The design for a top as herein shown and described.

In testimony that I claim the foregoing as my invention I have signed my name, in presence of the subscribing witnesses, this 13th day of May, 1899.

AUGUST SEILER.
